UNITED STATES PATENT OFFICE

THEODORE SHAPIRO, OF BROOKLYN, NEW YORK, ASSIGNOR TO RUBY LAMP MFG. CO., INC., OF NEW YORK, N. Y., A CORPORATION OF NEW YORK

DESIGN FOR A LAMP OR SIMILAR ARTICLE

Application filed April 8, 1933. Serial No. 47,727. Term of patent 3½ years.

To all whom it may concern:

Be it known that I, THEODORE SHAPIRO, a citizen of the United States, and a resident of the borough of Brooklyn, in the county of Kings, city and State of New York, have invented a new, original, and ornamental Design for a Lamp or Similar Article, of which the following is a specification, reference being had to the accompanying drawing forming a part thereof.

Fig. 1 is a top view of a lamp or similar article showing my new design;

Fig. 2 is an elevational view of the said lamp or similar article.

I claim:

The ornamental design for a lamp or similar article, substantially as shown.

In testimony whereof, I have signed my name to this specification this 3rd day of April, 1933.

THEODORE SHAPIRO.
